CLAIM

The ornamental design for a TV receiver, as shown and described.

DESCRIPTION

FIG. 1 is a front, right side, perspective view of a TV receiver showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a right side view of the design of FIG. 1, shown in an alternate oblique position with the bracket in an unfolded state thereof;

FIG. 10 is a front, right side, perspective view thereof;

FIG. 11 is another front view thereof, showing the state in which the user screen includes unclaimed digital media on the partially exposed display part according to the partially lowered position of the front panel thereon;

FIG. 12 is another front, right side, perspective view of the design of FIG. 1, shown in an alternate position for use wherein the display is fully exposed according to the fully lowered position of the front panel thereon;

FIG. 13 is a rear perspective view thereof;

FIG. 14 is a front view thereof;

FIG. 15 is a rear view thereof;

FIG. 16 is a left side view thereof;

FIG. 17 is a right side view thereof;

FIG. 18 is a top view thereof;

FIG. 19 is a bottom view thereof; and,

FIG. 20 is another front view thereof, showing the state in which the user screen includes unclaimed digital media on the fully exposed display part.

The broken lines showing the wall in FIGS. 9 and 10 and the broken lines showing the digital media on the screen in FIGS. 11 and 20 depict environmental subject matter only and form no part of the claim; while all other broken lines in the drawings depict portions of the TV receiver that form no part of the claimed design.
